United States Patent Office

Des. 185,265
Patented May 26, 1959

185,265

FOLDING BOX

Joseph D. Cudd, Boise, Idaho

Application March 8, 1957, Serial No. 45,161

Term of patent 14 years

(Cl. D58—12)

Figure 1 is a perspective view of a folding box showing the new design thereof.

Figure 2 is a view of the folding box of Figure 1, shown in an open position.

Figure 3 is an end elevational view thereof.

Figure 4 is a side elevational view thereof.

I claim:

The ornamental design for a folding box, as shown.
